MERCURY SWITCH

Application filed November 24, 1928. Serial No. 321,568.

This invention relates in general to mercury switches and more particularly to the type of mercury switches having an outer envelope and an inner protective element supported upon the outer envelope in spaced relation thereto.

The present invention aims to provide a mercury switch of this character wherein the inner protective element usually in the form of a tube of arc resistant material is supported and maintained in proper relation to the outer envelope in a simple, durable and effective manner and in such a way as to preclude the transmission of shocks and strains between the tube and the outer envelope while holding the protective element substantially rigid with respect to its envelope.

Another important object of the invention is to facilitate the production of a mercury switch of this character and in pursuance of this object the present invention proposes a novel method of making this type of mercury switch.

A further object is to provide a mercury switch having these advantages and capacities and which is of simple construction, which will stand up under the conditions of actual practice without disintegrating and contaminating the mercury and which is easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming a part of this specification, and in which:

40 Figure 1 is a view, partly in central longitudinal section and partly in elevation showing a mercury switch embodying the present invention, and illustrating the switch in circuit breaking position;

45 Figure 2 is a similar view showing the switch in circuit making position;

Figure 3 is a view in transverse section taken on line 3—3 of Figure 2;

50 Figure 4 is an enlarged fragmentary sectional view, the section being taken in the

same plane as that of Figures 1 and 2 but the showing being somewhat enlarged to better illustrate the construction whereby the inner tube is supported on the outer envelope; and

Figure 5 is a group view partly in section 55 and partly in elevation illustrating the steps of the method proposed by the present invention.

As shown in Figures 1 and 2, a mercury switch embodying the present invention comprises an outer envelope 1 which may be of soft glass or any other suitable material. Within the outer envelope 1 a protective element 2 is provided and is shown in the form of a tube which may be constituted of hard 60 glass, quartz, porcelain, or any other suitable arc resistant material. For the purpose of supporting the protective tube 2 upon the outer envelope and in spaced relation thereto, novel supporting means designated generally 70 at 3 is utilized. The supporting means 3 includes an integral or one-piece rigid ring 4 which may be of glass, aluminum oxide, or any other molded or cast material. The glass ring 4 is covered with a coating 5 of cement which, in the assembly, adheres to the outer periphery of the tube 2 and to the inner periphery of the envelope 1. Electrodes 6 and 7 are sealed in through the ends of the glass envelope and are constantly immersed in 80 bodies of mercury designated at 8 and 9, respectively. In the closed position of the switch the bodies of mercury designated at 8 and 9 unite on a surface 2' of the hard glass tube 2. Similarly, when the switch is moved to the circuit breaking position the bodies of mercury divide on the surface 2' of the glass tube 2.

The steps of the method by which this switch construction is produced are illustrated diagrammatically in Figure 5. As illustrated in Figure 5, the glass ring 4 is first coated with the covering 5 of cementitious material. This cementitious material is of such character and composition that it expands slightly when heated and sets in its expanded condition. While various cementitious substances may be utilized preferably the cement consists of sodium silicate and calcium carbonate in the proportions of four 95 100

pounds of calcium carbonate to five gallons of sodium silicate, the sodium silicate having a specific gravity of 42 degrees Baumé, and having a balanced composition in that it has a sodium oxide content of eight per cent and a silicon dioxide content of thirty per cent. The viscosity of the cement thus constituted is determined and either by drying or the addition of water this viscosity is varied until it is appropriate for the switches to be manufactured. The glass rings 4 are coated with this cement by a series of dipping operations with alternate drying. Usually three dipping operations are required to build up the requisite coating on the glass ring. Where air drying is employed between the dipping operations, the time of drying varies from 15 to 20 minutes, depending upon the prevailing humidity as determined by a hygrometer. After the glass ring has been properly coated and dried it is assembled with one end of the protective tube 2 and the protective tube and glass ring are then inserted in the outer envelope 1 which, in its original condition, is open at both ends, as illustrated in Figure 5. The assembly is then placed in an oven and is heated to a rather high temperature, usually from 320 to 400 degrees centigrade. The temperature of the oven is raised slowly and preferably over a period of 5 to 10 minutes and the temperature is held at the highest point for approximately thirty minutes. This causes the calcium carbonate and the sodium silicate to react and set, thus forming the constituent parts of soda lime glass and evaporating the free or occluded moisture. During this heating the cement expands slightly and while the expansion is sufficient to cause the covering of cement to tightly engage and adhere, not only to its ring 4 but also to its envelope 1 and tube 2, the expansion is not of such amount as to crack any of the parts. The switch is then removed from the oven after cooling and following inspection is subjected to an annealing operation which consists in raising the temperature of the switch as thus far made to a point just under fusing temperature, which is usually somewhere from 500 to 600 degrees centigrade. The temperature is held at this point for a period ranging from 10 to 15 minutes and the switch is then slowly cooled. This relieves any strains that may have been set up and permits the different parts to adjust themselves to the conditions of assembly. After this phase of the method the manufacturing process is conventional in that the ends of the outer envelope are closed in the usual manner, the electrodes sealed therethrough in accordance with conventional practice, the mercury placed within the switch through the usual tubulation or sealing tip 10 and the air exhausted and an atmosphere of inert gas supplied through this

sealing tip after which the tip is fused and sealed.

A mercury switch constructed in this manner rigidly maintains the inner protective tube in proper position within the outer envelope and out of contact therewith. While the composite supporting structure is sufficiently rigid to maintain this relation between the parts and is sufficiently durable to stand up under the conditions that result from the operation of the switch, nevertheless, the covering of the cement on the ring 4 has a yieldable or resilient property which enables it to take up the shocks or strains resulting from arcing and precludes the transmission of these shocks and strains between the inner protective tube and the outer envelope. And the cement thus constituted and applied will not disintegrate or contaminate the mercury and impair the support of the protective tube. The rigid ring embedded in the cement gives the composite supporting structure qualities of strength and rigidity and aids in maintaining its structural integrity. The required amount of yieldability is supplied by the cement. Further, as the adhesion of the cement to the envelope and protective tube results from the expansion of the cement following its heating, this adhesion is uniform over a large area to distribute the load of support over a large area of the outer envelope. While these advantages are realized, the manufacture of the switch is simplified and may be carried out with economy. Obviously, quite a large number of rings may be simultaneously coated with cement by utilizing a tray on which the rings are supported for dipping. The assembly operation consists merely of the fitting of a prepared ring on the inner tube and the interfitting of the assembled tube and ring with the glass envelope. The fixing of these parts in this position follows from the subsequent heating operation.

Another advantage of this type of support is that it prevents the mercury from lodging therein and finding its way therethrough and producing a short-circuit, although it has sufficient porosity to prevent entrapment of gas in any zone or compartment of the switch. The ring itself, of course, has no porosity but the cement has such a limited amount of porosity to permit of the seepage of gas therethrough. However, the cement is of such a dense and compact construction as to preclude the mercury from finding its way therethrough or infiltrating therein even when the mercury is thrown against the partition under heavy pressures.

The invention claimed is:

1. A mercury switch comprising an outer envelope, an inner protective tube of arc resistant material, and means for supporting the tube on the envelope, and including a supporting ring of glass interposed between the tube and the envelope and a body of

cement covering the ring and adhering thereto and to the tube and envelope.

2. A mercury switch comprising an outer envelope, a protective element of arc resistant material in said envelope, and means for supporting the protective element on the envelope and comprising a body of cement interposed between the protective element and the envelope and having a rigid supporting element embedded therein.

3. A mercury switch comprising an outer envelope, a protective element of arc resistant material therein, and means for supporting the protective element on the envelope and comprising a rigid supporting element interposed between the protective element and the envelope, and yieldable means between the rigid supporting element and the envelope and the supporting element and the protective element.

4. A mercury switch comprising an outer envelope, a protective element of arc resistant material therein, and means for supporting the protective element on the envelope and comprising a rigid supporting element interposed between the protective element and the envelope, and a yieldable covering on the rigid supporting element engaging the envelope and the protective element.

5. A mercury switch comprising an outer envelope, a protective element of arc resistant material therein, and means for supporting the protective element on the envelope and comprising a supporting element interposed between the protective element and the envelope, and yieldable layers interposed between and having holding engagement with the protective element and the supporting element and the envelope and the supporting element.

6. A mercury switch comprising an outer envelope, a protective element of arc resistant material therein, and means for supporting the protective element on the envelope, and comprising a rigid supporting element interposed between the protective element and the envelope, and layers of material having cementitious properties interposed between and adhering to said supporting element and said envelope and said supporting element and said protective element.

7. A mercury switch comprising an outer envelope, a protective element of arc resistant material therein, and means for supporting the protective element on the envelope and comprising a rigid supporting element interposed between the protective element and the envelope, and cement associated with the supporting element and acting to maintain the protective element in position while minimizing the transmission of shocks and strains between the protective element and the envelope.

8. In a device of the character described having tubular structures located one within

the other, means for supporting one tubular structure on the other including a body of cement interposed between said structures and having a rigid supporting element embedded therein.

9. In a device of the character described having tubular structures located one within the other, means for supporting one tubular structure on the other including a rigid supporting element interposed between said structures and cement associated with the supporting element and completing the supporting action thereof while minimizing the transmission of shocks and strains.

10. In a device of the character described having tubular structures located one within the other, means for supporting one tubular structure on the other including a body of yieldable adhesive material and a glass ring embedded therein.

11. Means for supporting an element of a mercury switch in position therein including a hard and rigid supporting member interposed between the element and the part of the switch on which it is supported and layers of material adhering to said member and to said element and said part and supporting said element in position while minimizing the transmission of shocks and strains.

12. The herein-described method of making a mercury switch structure which consists in coating a rigid ring with a substance which expands and sets under the action of heat, assembling the ring together with an inner protective element and an outer casing, and subjecting the assembly to heat.

13. The herein-described method of making a mercury switch structure which consists in coating a supporting member with a substance which expands and sets under the action of heat, assembling the supporting member with the parts of the switch structure which it is designed to maintain in proper position and relation, and subjecting the assembly to the action of heat.

14. The herein-described method of making a mercury switch structure which consists in coating a supporting member with a substance which expands and sets under the action of heat, assembling the supporting member with the parts of the switch structure which it is designed to maintain in proper position and relation, baking the assembly to cause said substance to expand and set, and subsequently annealing the assembly.

15. The herein-described method of making a mercury switch structure which consists in coating a supporting member with a cementitious substance which expands and sets under the action of heat and which when set has sufficient yieldability to prevent transmission of shocks and strains therethrough, assembling the coated supporting member with the parts of the switch structure it is designed to maintain in proper position and

subjecting the assembly to heat to expand and set the covering of cement.

16. The herein-described method of making a mercury switch structure which consists in coating a supporting member with a cementitious substance having the property of expanding and setting under the action of heat by successively dipping the supporting member in such substance, permitting it to dry in between dipping operations, assembling the supporting member so coated with parts of the switch structure which it is designed to maintain in proper position and relation and subjecting the assembly to heat to expand and set the cementitious coating.

17. The herein-described method of making a mercury switch which consists in coating an integral supporting member with a cementitious substance consisting of an aqueous solution of sodium silicate and calcium carbonate, allowing the coating to dry, then assembling the coated supporting member with the parts of the switch structure which it is designed to maintain in proper position and relation and subjecting the assembly to heat to cause the calcium carbonate and sodium silicate to react and to form the constituent parts of soda lime glass and evaporate to free or occluded moisture whereby the coating expands and sets to rigidly maintain the parts of the switch in position while precluding the transmission of shocks and strains.

18. The herein-described method of making a mercury switch structure of the type having an inner protective tube of arc resistant material assembled in an outer envelope in spaced relation thereto which consists in successively dipping an integral glass ring in a cement solution and allowing the coating to dry on the ring intervening the dipping operations, assembling the ring after its coating has dried with the tube and assembling the tube and ring with the envelope and finally heating the assembly to cause the cement to expand and set to maintain the parts in proper position and relation.

19. A mercury switch of the character described including an outer envelope, an inner protective tube of arc resistant material, and a composite supporting member between the tube and the envelope and comprising a rigid integral ring and a coating of cementitious material expanded in the assembly to adhere to the ring and to the tube and to the envelope for rigidly holding the parts in proper position and relation while precluding the transmission of shocks and strains.

20. A mercury switch of the character described including an outer envelope, an inner protective tube of arc resistant material, and a composite supporting member between the tube and the envelope and comprising a rigid integral ring and a coating of cementitious material consisting of sodium silicate

and calcium carbonate adhering to the ring and to the tube and to the envelope for rigidly holding the parts in proper position and relation while precluding the transmission of shocks and strains.

In witness whereof, I hereto affix my signature.
